UNITED STATES PATENT OFFICE

2,160,265

BIT HEATING APPARATUS

Louis A. Galambos, Jr., Kansas City, Mo., assignor
to Sullivan Machinery Company, a corporation
of Massachusetts

Application November 20, 1936, Serial No. 111,894

3 Claims. (Cl. 214—21)

This invention relates to furnaces, and more particularly to improvements in furnaces for heating mining machine cutter bits and means for supporting and conveying the bits with respect to the furnace.

An object of this invention is to provide an improved furnace for heating mining machine cutter bits preparatory to the hard facing of the bit cutting points. Another object is to provide an improved supporting and conveying means for supporting the bits and for conveying the bits with respect to the furnace. Other objects and advantages of the invention will, however, hereinafter more fully appear.

In the accompanying drawings there is shown for purposes of illustration one form which the invention may assume in practice.

In these drawings,—

Fig. 1 is a plan view of the improved furnace and the associated bit supporting and conveying means.

Fig. 2 is a side elevational view of the furnace and bit supporting and conveying means shown in Fig. 1.

Fig. 3 is a vertical sectional view taken substantially on line 3—3 of Fig. 1.

Fig. 4 is a horizontal sectional view taken substantially on line 4—4 of Fig. 3.

Fig. 5 is a perspective view of a mining machine cutter bit of improved form, adapted to use with the improved furnace and bit supporting and conveying means.

Fig. 6 is a side elevational view of the improved cutter bit.

In this illustrative embodiment of the invention there is shown a furnace generally designated 1, having associated therewith an improved bit supporting and conveying means generally designated 2. The furnace 1 comprises a casing 3 of generally rectangular form mounted on a support 4 and lined internally with fire brick 5 to form a heating chamber 6. This heating chamber has a lateral flue opening 7, and a combustible mixture is supplied to the heating chamber 6 by a conventional burner 8.

Now referring to the improved bit supporting and conveying means 2, it will be noted that a pedestal 9 having a base 10 has journaled thereon at 11 a revoluble table 12 herein in the form of a circular plate having secured near the peripheral edge thereof an annular bit support 13. This bit support is provided with relatively inclined supporting surfaces 14 and 15, so that the bits generally designated 16 are supported thereon in the inclined position, as shown most

clearly in Fig. 3, with the cutting portions 17 of the bits located near the outer rim of the annular support.

In Fig. 5 there is shown a cutter bit of an improved type comprising a usual shank 18 and a relatively inclined portion 19 on which the cutting portion 17 is formed. The cutting portion 17 of the bit is preferably formed on a forging machine of the type disclosed in the patent to S. T. Nelson, 1,650,580, patented Nov. 22, 1927, and the cutter bit herein is generally similar to that disclosed in the S. T. Nelson patent, No. 1,679,049, patented July 31, 1928. In this instance, the forward cutting face of the bit is formed with a double taper at 20 and 21 to obtain increased strength, and a hard abrasive material is applied to the outer inclined surface 21 at 22 to increase the wearing qualities of the bit cutting point. It will be evident that the cutter bit used herein may be formed in any suitable manner and that bits of types other than that disclosed may be heated and hard faced in accordance with the present invention, although the bit disclosed, due to its improved design, is preferable to other known types.

The cutter bits to be heated, subsequent to the forming or sharpening process, are placed on the revoluble table in the manner clearly shown in Fig. 2, with the bit shanks engaging the inclined surface 15 of the annular support and the receding surfaces of the cutting portions of the bit engaging the relatively inclined surface 14 of the support. When the bits are so arranged, the inclined surface 21 of the bit is located near the outer rim of the annular support. As the bits are placed on the annular support, the table is rotated so as to move the bits within the heating chamber 6 of the furnace, the annular support for the bits moving within the lateral flue opening of the heating chamber in the manner shown in Fig. 3, so that the cutting portions of the bit are subjected to the direct heat of the furnace. When the cutting portions of the bits are heated to the proper temperature, the table is revolved to move the bits from the heating chamber of the furnace, and as the bits are moved from the furnace the operator applies, by means of an acetylene torch, a hard abrasive substance to the faces 21 of the cutting portions of the bits, the bits being supported on the annular support in the inclined position above mentioned, so that the cutting portions of the bits are presented in a more convenient manner, thereby to facilitate the application of the hard faces to the bits.

As a result of this invention, it will be noted

that an improved bit heating furnace, together with an improved bit supporting and conveying means is provided whereby the heating process is substantially continuous, and as the heated bits are discharged from the furnace, they are supported in position convenient for hard tipping, the operator applying a hard abrasive substance to the bit points as the bits are discharged from the furnace. It will further be noted that by the provision of the improved bit supporting and conveying means the bits are moved in an improved manner with respect to the furnace, and are supported in an inclined position in an improved manner to facilitate the hard facing of the cutting points. It will also be noted that the improved bit supporting and conveying means and the associated furnace are of an extremely simple and rugged design which may be manufactured at a minimum of expense. Other uses and advantages of the improved furnace and bit supporting and conveying means will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a bit heating apparatus, the combination of a furnace having a heating chamber provided with a horizontal opening curved inwardly in plan for receiving the bits to be heated, and a horizontal rotary carrier having a portion annular in plan disposed at one side in adjacency to said chamber opening and shaped to conform to said curved chamber opening for providing a closure for the chamber opening, said annular carrier portion having at its exterior periphery an annular bit support for supporting a series of the bits to be heated, said carrier upon rotation

thereof moving the bits to be heated within said furnace heating chamber, said annular carrier portion serving both as a bit support and a closure for said chamber opening.

2. In a bit heating apparatus, the combination of a furnace having a heating chamber provided with a horizontal opening curved inwardly in plan for receiving the bits to be heated, and a horizontal rotary carrier having a portion annular in plan disposed at one side in adjacency to said chamber opening and shaped to conform to said curved chamber opening for providing a closure for the chamber opening, said annular carrier portion having at its exterior periphery an annular bit support providing relatively inclined supporting surfaces for supporting a series of the bits to be heated in an inclined position with the lower portions of the bits nearer the outer periphery of said carrier, said carrier upon rotation thereof moving the bits to be heated within said furnace heating chamber, said annular carrier portion serving both as a bit support and a closure for said chamber opening.

3. In a bit heating apparatus, the combination of a furnace having a heating chamber provided with a horizontal opening curved inwardly in plan for receiving the bits to be heated, and a horizontal rotary carrier having a portion annular in plan disposed at one side in adjacency to said chamber opening and shaped to conform to said curved chamber opening for providing a closure for the chamber opening, said annular carrier portion having at its exterior periphery an annular bit support providing relatively inclined supporting surfaces for supporting a series of the bits to be heated in an inclined position with the cutting portions of the bits located nearer the outer periphery of said carrier, said carrier upon rotation thereof moving the cutting portions of the bits to be heated within said furnace heating chamber, said annular carrier portion serving both as a bit support and a closure for said chamber opening.

LOUIS A. GALAMBOS, JR.
